CLAIM

The ornamental design for an inhalator, as shown and described.

DESCRIPTION

FIG. 1 is a front elevational view of an inhalator showing our new design;

FIG. 2 is a rear elevational view thereof;

FIG. 3 is a top plan view thereof;

FIG. 4 is a bottom plan view thereof;

FIG. 5 is a right side elevational view thereof, the left side elevational view being a mirror image thereof;

FIG. 6 is a right side elevational view thereof shown in a closed position; and,

FIG. 7 is a cross-sectional view thereof, taken along line 7—7 of FIG. 1.
